UNITED STATES PATENT OFFICE

CRAWFORD C. LOOMIS, OF ILION, NEW YORK, ASSIGNOR TO REMINGTON ARMS COMPANY, INC., A CORPORATION OF DELAWARE

FIREARM

Application filed October 17, 1928. Serial No. 312,960.

This invention relates to firearms, particularly firearms of the so called "repeating" type, in which a number of cartridges are stored in a magazine forming a part of the firearm and are transferred from the magazine, one at a time, to the firing chamber by the manual operation of a suitable element, such as a bolt, lever, or sliding forearm.

In guns of this type, the first operation which is performed upon the manipulation of the operating element is the unlocking of the chamber closing breech block, and this operation is followed by the retraction of such block to open the chamber. Incidental to the retraction of the breech block, the fired shell in the chamber is withdrawn or "extracted" by means of suitable devices generally associated with the breech block. The "extractor" device frequently consists of a spring controlled hook mounted in or associated with the breech block and adapted to engage the rim of the shell in the chamber to extract the shell during the retracting movement of the breech block. The shell, when fully withdrawn from the chamber, is thrown clear of the firearm through a suitable opening in the receiver by the action of a suitable ejector device which becomes effective when the fired shell reaches the proper position.

Owing to the high breech pressure which is developed in firing modern cartridges, the cartridge case or shell is expanded to closely engage the walls of the firing chamber and considerable force may be necessary to extract it therefrom. When the extractor device consists of a single hook engaging the rim of the shell at one point only, considerable difficulty may at times be experienced in readily extracting the shell. The metal constituting the rim which is engaged by the hook may even be bent or sheared, permitting the withdrawal of the hook leaving the empty shell in the chamber. Such a hook at best engages the shell rim at one side only and the extracting force is thus not in alignment with the resultant of the frictional resistance which opposes the withdrawal of the shell.

It is an object of this invention to provide

an improved extractor mechanism which will insure the extraction of even very tightly fitting shells. It is a further object of the invention to provide an extractor which so engages the shell that the extracting force is supplied substantially in alignment with the resultant of the resisting force. It is a further object of the invention to provide an extractor device so related to the breech block and to the chamber that when the breech block is moved to unlocked position ready to begin its rearward movement, the extractor will engage the rim of the shell in a plurality of positions. It is a further object of the invention to provide an extractor device which, when the shell reaches the proper position for ejection will act to assist the ejection thereof and to provide positively acting ejectors which work in conjunction with such extractor.

In the drawings, Fig. 1 is a fragmentary longitudinal sectional elevation of a firearm embodying the present invention, the breech being closed and locked.

Fig. 2 is a fragmentary longitudinal sectional elevation showing the breech unlocked and the extractors in engagement with the shell rim ready to withdraw the shell from the chamber.

Fig. 3 is a fragmentary longitudinal sectional elevation showing the breech block retracted to shell ejecting position.

Fig. 4 is a plan view of the receiver, the top wall being removed to show the interior mechanism.

Fig. 5 is a transverse sectional elevation substantially on line 5-5 of Fig. 1.

The invention as illustrated is applied to a firearm of the type described in the U. S. patents to Pedersen #719,955, Feb. 3, 1903, and #789,932, May 16, 1905, although it will be understood that it is readily applicable to firearms of other types.

The firearm comprises a barrel 10 and a cartridge containing magazine 11, both of which are secured to the forward end of a receiver 12 which contains the fire control mechanism. The firing chamber is closed by the breech block 13 comprising a slot 14, adapted to receive a lug carried at the rear-

ward end of an action bar 15 (Fig. 1) which extends forward from the receiver along the magazine tube 11 and is operated by means of the usual sliding forearm (not shown).
5 The cartridges, which are arranged in column in the magazine 11 are removed therefrom one at a time and transferred to a position in alignment with the firing chamber by means of the carrier device 16 mounted 10 on the longitudinally extending spindle 17 in one side of the receiver. The carrier is operated by means of suitable control surfaces on the breech block and is more fully described in the above mentioned Pedersen 15 patents. In its breech closing position the breech block is locked by the engagement of the upper part of its rearward end with a shoulder 18 on the receiver, as illustrated in Fig. 1. When the action bar 15 is retracted, 20 owing to the inclination of the slot 14 the breech block is first rocked about the lower edge of its forward face lowering the rear end out of engagement with the shoulder 18 to the position shown in Fig. 2. Further 25 rearward movement of the action bar retracts the breech block to the position shown in Fig. 3. A firing pin or striker 19 which is urged forward by spring 20 extends longitudinally through the breech block and is 30 adapted to be controlled by sear 21 operated by a trigger 22 pivoted at 23. The foregoing devices are more fully illustrated and described in the above mentioned Pedersen 35 patents.

35 The form of the improved extractor device of the present invention which has been chosen for the purpose of illustration is constructed as follows:

A lower extractor hook 24 is supported 40 on a transverse pivot 25 in the upper portion of the breech block, the breech block being suitably recessed to receive it. The upwardly extending part of this hook is laterally offset from the hook and the forwardly 45 extending shank which carries it to provide the proper clearance for the firing pin. The hook is also provided with an upwardly extending tongue 26 carrying a pivot 27 upon which a tension arm 28 is pivoted. The arm 28 extends forward, lying in a groove in the breech block, is offset upwardly a short distance from its forward end, and terminated in a downwardly inclined face 281. Adjacent the face 281 on the lower edge of the 50 arm is a arcuate recess or notch 282 adapted to engage the rim of the shell. The tension arm 28 also extends rearwardly from the pivot 27 and is provided with a shoulder 29 adapted for engagement by a nose 30 which 55 is integral with the hook 24. An aperture 31 in the arm 28, located between pivot 27 and shoulder 29, receives one end of a spring 32 which is coiled about the pivot 25 and bears upon a suitable surface in the breech 60 block. The spring thus tends to draw the 65

arm 28 downwardly, and if the shoulder 29 is in contact with the nose 30 the hook 24 is drawn upwardly.

The position of the extractor device when the breech is locked is shown in Fig. 1. It will 70 be seen that while the hook 24 is in engagement with the shell rim the notch 282 stands somewhat forward and slightly above the shell rim, the inclined face 281 resting upon the similarly inclined end of a recess in the 75 chamber wall. The offset end of arm 28 lies in a recess 121 in the top of the receiver. When the breech is unlocked it is rocked from the Fig. 1 position to the Fig. 2 position as heretofore described and in this movement 80 the arm 28 moves rearwardly, the notch 282 engaging the shell rim as illustrated in Fig. 2. Thus, in this position when the breech block is ready to begin its rearward movement, both hook 24 and notch 282 firmly engage the shell rim, at substantially diametrically opposite points. The extracting force applied through them is therefore in alignment with the center of the frictional resistance which opposes the extraction of the 85 shell, and its extraction is thus facilitated.

As the breech block moves rearwardly it is gradually lowered, but it is obviously desirable that the shell head remain substantially in alignment with the chamber until the shell mouth is clear of the chamber. To secure this result the breech block recess containing the hook 24 is cut deep enough to permit this hook and with it the entire extractor device to move upward to the position shown in Fig. 3. This movement is facilitated by spring 32, which tends to rock the extractor device clock-wise about its pivot 25. Thus as the breech block moves rearwardly the extractor device moves, with respect to the breech block, from the Fig. 2 position to the Fig. 3 position, the shell being held thereby in substantial alignment with the chamber. During the greater part of this movement the offset forward end of arm 100 28 traverses a guide groove 121 in the top of the receiver.

At about the position shown in Fig. 3 the shank of hook 24 engages the bottom 131 of its recess in the breech block stopping the upward movement of the extractor device. The shell head is then carried downward slightly, and is then engaged by the fixed ejector lugs 33 and 331 (Figs. 3 and 5). Substantially simultaneously the shoulder 29 of arm 28 engages breech locking shoulder 18 and the upper side of arm 28 opposite the pivot 27 contacts with the top wall of the receiver at 35. The extractor device is thus rocked quickly in a counter clockwise direction, the shell being similarly turned by the combined action of hook 24, lugs 33 and 331, and arm 28, and is forcefully ejected thru the loading and ejecting opening in the bottom of the receiver.

When the action is closed the hook 24 rests against the rim of the shell in the chamber or in the absence of a shell against the inclined end of the barrel. It will be noted that when the gun is "taken down" by removing barrel or barrel and magazine assembly from the receiver, the breech block being in or adjacent to its forward position, upward movement of the hook 24 is prevented by the engagement of the projection 26 with the receiver top. Displacement of the extractor device and particularly movement of the hook across the face of the breech block to a position in which it would interfere with replacement of the barrel is thus prevented.

Variations and modifications of the precise construction shown and described may be made within the scope of the appended claims, which are to be broadly construed.

20 What is claimed is:

1. In a firearm in combination a cartridge containing chamber, a breech block adapted to close said chamber, an extractor device associated with said breech block comprising a pivoted extractor hook, and a tension arm comprising a notch adapted to engage the rim of a shell in said chamber pivoted to the extractor hook.

2. In a firearm a cartridge containing chamber, a breech block adapted to close said chamber by its longitudinal movement and to be locked in chamber closing position by a rotary movement, an extractor device comprising a plurality of elements adapted to engage the rim of a cartridge in said chamber at spaced points, one of said elements being out of engagement with said rim when said breech block is locked, and moved into engagement with said rim by the rotary movement of said breech block to unlocked position.

3. In a firearm comprising a chamber, a chamber closing breech block and a breech block housing receiver, an extractor device mounted in said breech block comprising elements adapted to engage the shell rim at relatively spaced positions, one of said elements being positively held in engagement with the shell rim by contact with said receiver, and being yieldable to release the shell rim for ejection of the shell.

4. In a firearm comprising a chamber, a breech block adapted to close said chamber and to be retracted to a position out of alignment with said chamber, an extractor device mounted in said breech block adapted to engage the rim of a shell in said chamber and being movable relative said breech block to hold said shell in alignment with said chamber while the breech block moves out of such alignment.

5. In a firearm comprising a chamber and a chamber closing breech block, a device for extracting shells from said chamber mounted in said breech block and comprising elements

adapted to engage the rim of a shell in said chamber at spaced points, a control spring urging the shell rim engaging elements upward relative to said breech block, and means for limiting said upward movement of said elements. 70

6. In an extractor device for firearms an extractor hook adapted to engage the rim of a shell and a tension arm comprising a shell rim engaging notch pivoted to the extractor hook. 75

7. In an extractor device for firearms, an extractor hook adapted to engage the rim of a shell, a tension arm having a shell rim engaging notch pivoted to the first extractor hook, a spring urging the free ends of said hooks and said tension arm toward each other, and interengaging abutments on said hooks and said arm limiting their movement toward each other by said spring. 80

8. In a firearm comprising a breech block, an extractor device mounted in said breech block and comprising a plurality of shell rim engaging elements, means whereby said elements are permitted a limited individual movement with respect to said breech block, and means permitting said device a unitary movement with respect to said breech block while its elements remain relatively fixed. 85

9. In a firearm comprising a chamber, a breech block and a breech block housing receiver, an extractor device mounted in said breech block, means for effecting movement of said extractor device relative to said breech block during a part of its movement 90 whereby the shell is held in alignment with said chamber until clear thereof, and means positively restoring said extractor device to normal position relative to said breech block thereby facilitating the ejection of the shell 100 from the receiver.

10. In a firearm, a breech block, an extractor device comprising an extractor hook pivoted in said breech block, a tension arm comprising a shell rim engaging notch pivoted upon said extractor hook, a spring urging the free ends of said hook and said arm toward each other, and interengaging abutments on said hooks limiting their movement by said spring. 115

11. In a firearm comprising a chamber, a breech block adapted to close said chamber and to be retracted to a chamber opening position out of alignment with said chamber, a receiver housing said breech block, a device 120 for extracting shells from said chamber mounted in said breech block, means for maintaining said extractor device in alignment with said chamber during a substantial part of the retractive movement of said breech block, an ejector lug in said receiver adapted to engage the head of the shell near the end of the retractive movement of the breech block and means associated with said receiver for positively restoring the extractor 125 130

device to normal position in the breech block substantially simultaneously with the engagement of the shell head with said ejector lug.

- 5 12. In a firearm comprising a barrel, a receiver and a breech block housed in said receiver, an extractor device mounted in said breech block and comprising an extractor member projecting from the forward face of
- 10 said breech block adapted for movement transversely of said face, means whereby the barrel prevents transverse movement of the extractor member, and supplemental means integral with the receiver for preventing transverse movement of the extractor when the barrel is removed.
- 15 13. In a firearm, a breech block, an extractor device carried by said breech block comprising a pivoted extractor claw and a shell rim engaging arm pivoted on said claw.
- 20 14. In a firearm, a receiver, a reciprocable breech block therein, an extractor device carried by said breech block adapted to engage the rim of a cartridge shell, said extractor
- 25 device being movable transversely relative to said breech block, and means carried by said receiver engageable with said extractor device during the extracting movement of said breech block to impart a transverse shell
- 30 ejecting movement to said extractor device.
